UNITED STATES PATENT OFFICE.

THOMAS BURKE, OF CLEVELAND, OHIO, ASSIGNOR OF ONE-THIRD TO FREDERICK A. LEATNOW AND ONE-THIRD TO LOUIS BERNSTEIN, BOTH OF CLEVELAND, OHIO.

COMPOUND RAILWAY-RAIL.

1,141,766.

Specification of Letters Patent.

Patented June 1, 1915.

Application filed January 2, 1915. Serial No. 119.

To all whom it may concern:

Be it known that I, THOMAS BURKE, citizen of the United States, residing at Cleveland, in the county of Cuyahoga and State of Ohio, have invented certain new and useful Improvements in Compound Railway-Rails, of which the following is a specification.

This invention relates to railway rails, 10 and especially to compound rails of that type in which the base and the tread or head are made in separate parts.

By means of this construction the tread can be renewed without disturbing the base 15 part, and therefore the rail is particularly serviceable in street railways, since the tread can be renewed without disturbing the pavement to any great extent, as would be necessary were the entire rail removed.

20 The invention includes improved means for fastening the head or tread part on the base.

The invention is illustrated in the accompanying drawings in which—

25 Figure 1 is a cross section showing fish-plates on the bottom or base sections. Fig. 2 is a similar view without the fish-plates. Fig. 3 is a section of a modification, showing the rail cap held in place without a bolt. 30 Fig. 4 is a similar view showing a crimp between the flanges of the head and the web, to hold the former in place. Fig. 5 is a side elevation of the construction shown in Fig. 1. Fig. 6 is a side elevation of the construction shown in Figs. 3 and 4.

Referring specifically to the drawings, 7 indicates the base of the rail and 7^a the web integral therewith. The top part 7^b of this web is slightly enlarged, and is wedge 40 shaped, as shown, and is provided with longitudinal grooves or recesses 7^c along the opposite sides thereof.

8 indicates the head of the rail which forms the tread, and is removable. This 45 head is provided on its under side with longitudinal flanges 8^b, depending on opposite sides, with a wedge shaped space therebetween as indicated at 8^a, adapted to fit on the upper part of the web. In the 50 form shown in Figs. 1 and 2 the head is connected to the web by rivets 9 extending through the web and the said flanges. In

this form, the recesses 7^c serve to prevent corrosion between the web and the flanges, the hollow space formed by the recesses 55 breaking the rust that gathers between said web and flanges when the parts are exposed to dampness and water, and permit easier removal of the head than if the meeting surfaces were continuous. The base sections 60 are connected by fishplates 10 on opposite sides of the web, and rivets 11 extending through the fish-plates and the web. By the means disclosed, the head may be removed for renewal, by taking out the rivets 9 and 65 putting a new head in place.

In the form shown in Fig. 4 the rivets are unnecessary, and the head is held onto the web by crimps or bosses 8^c which are “spotted” or forced into the recesses 7^c at 70 suitable points along the same, by means of a suitable tool or device, these bosses engaging in the recesses to hold the head on the web without the use of bolts or rivets. To remove the head, the bosses are pried 75 out by a suitable crow-bar or tool, and the head forced off of the web.

In either construction, it is unnecessary to remove the bottom part of the rail, and necessary renewal of the heads can be made, 80 as in a street railway, by simply taking up a row of blocks or a narrow strip of the pavement on each side of the rail to give room for work on the fastening devices.

What I claim as new is:—

1. A compound rail comprising a base having a web integral therewith, the opposite sides of the web having longitudinal recesses along the same, a head having depending flanges fitting on opposite sides 90 of the web and covering said recesses, fastening means between said web and flanges, and separate fastening means between the webs of adjacent rails.

2. A compound rail comprising a base 95 having a web thereon, said web having recesses on opposite sides thereof, and a head having depending flanges fitting against the opposite sides of the web, the flanges having bosses pressed into said recesses to hold the 100 head on the web.

3. A compound rail comprising a base having a web thereon provided with longitudinal recesses along opposite sides thereof,

and a head having depending flanges pressed at intervals into said recesses to form bosses engaging therein.

4. A compound rail comprising a base having a web thereon with a wedge shaped upper part having recesses in opposite sides thereof, and a head having depending flanges fitting on said upper part, the flanges being pressed into said recesses at different

points along the same, to form engaging 10 bosses.

In testimony whereof, I affix my signature in presence of two witnesses.

THOMAS BURKE.

Witnesses:

LOUIS BERNSTEIN,
JOHN A. BOMMHARDT.
